BUILDING CONSTRUCTION

Charles S. Wenzel, Houston, Tex., assignor of
one-fifth to J. P. Markham, Jr., and two-fifths
to M. C. Jarvis, both of Houston, Tex.

Application September 25, 1936, Serial No. 102,444

8 Claims. (Cl. 72—46)

The invention relates to building constructions and has reference to specific constructions in which building panels or other building elements such as moldings, baseboards and doorbucks are attached to supporting structures.

In the construction of buildings a common procedure is to provide a steel frame-work to which is secured reenforced concrete slabs to serve as floors, ceilings and outer walls. It is also common to provide partitions having a suitable frame-work frequently of metal. Such slabs and frame-work are usually provided with a suitably finished coating such as a synthetic wear resistant composition, plaster or the like in order that the desired finish may be obtained. In such constructions provision must be made for suitably securing in place such building elements as partitions, moldings, baseboards, etc. Difficulties are encountered in suitably anchoring such elements in the type of construction just mentioned and the present invention is concerned with problems thus presented. Such difficulties are increased in a case of anchoring of partitions for it is frequently desirable that the anchoring shall be such that the partition may be changed without destruction thereof and yet that the anchoring is effective when the partition is in place. It is therefore an object of the present invention to provide in a building construction an improved system of removably securing a partition in position.

Another object is the provision of a bendable anchoring channel which may be removably secured to a building structure and to which may be fixed an anchor strip of suitable material.

A further object is a building construction in which a bendable channel member and anchoring strips are secured to a supporting structure and utilized as a screed when applying a coating to the supporting structure.

The invention possesses numerous other objects and features of advantage, some of which, together with the foregoing, are set forth in the following description of specific structures embodying and utilizing the invention in a practical manner. The description is to be considered as illustrative only as other embodiments of the invention will be apparent to the skilled artisan. It is intended, however, that the invention shall be construed only in the light of the prior art and the appended claims.

In the drawing:

Fig. 1 is a sectional view of a building construction in which the invention is practically used

for securing the partition and cooperating elements in position.

Fig. 2 is a sectional view illustrating, in a general way, the manner in which the invention is practically applied.

Fig. 3 is a perspective view of a bendable channel used in practicing the invention.

Fig. 2 represents a cross-section of a portion of a building such as floor, ceiling or wall in which 1 represents a base material such as hollow tile, masonry, concrete or cement. To such base is usually applied a suitable surface coating 2. In order to illustrate generally the method of practicing the invention a channel assembly 3 is shown. This assembly may be applied before 10 coating 2 is applied or may be subsequently applied by removing a portion of the coating 2 to permit application of the assembly.

The assembly comprises a channel 5 (see Fig. 3), of bendable material which is provided with 20 holes 6 and 7 in the webs and flanges respectively. While this is the preferred construction, it is apparent that, since channel 5 is of relatively light metal, the pre-formed holes may be omitted and desired holes made by piercing the metal 25 with the respective fasteners that pass therethrough as hereinafter set forth. Assembly 3 is secured to the base 1 by driving nails 10 through the web or channel 5 and into base material 1 in order to anchor the member. A filler strip 8 30 is then positioned in the channel and is securely held therein by flange fasteners 9 such as nails or screws. The strip 8 may be of any suitable material, wood being preferable, as will be apparent from the complete disclosure of the invention. From this general illustration of the principles of the invention it is apparent that the attachment of any structural element to the base 1 may be accomplished by fastening or positioning of a channel assembly 3 as described at the 35 desired location.

Fig. 1 illustrates a practical use of the invention when removably securing a partition between ceiling 11 and floor 12. In such case a channel assembly 3 is secured to each the ceiling 45 11 and the floor 12 in the proper position for a partition generally designated as 15. Coatings 2 are then applied, the channel assembly 3 serving as a screed when applying such coatings.

The partition generally designated as 15 comprises a frame-work 16 to which is attached a layer of expanded metal or wire mesh which is suitable for receiving and holding wall coatings 2 of suitable material. It is to be understood that the coatings on floor, partition and ceiling may 50 55

be of similar or different compositions to satisfy requirements in a given instance.

- Frame-work 16 is secured to filler strip 11 in any suitable manner as, for example, by mortise and tenon joint as shown at 17 in Fig. 1. If this type of joint is used obviously the respective members of the frame 16 may be sprung slightly to permit entry of the ends thereof into the mortise in filler strip 8. Other suitable and well known methods of securing frame 16 to the channel assembly may be utilized. Frame-work 16 and mesh 19 having been assembled the partition is completed by application of wall coatings 2.
- 15 The construction for securing the partition in place is but one illustration of a practical application of the invention. Fig. 1 shows that application of the invention in the positioning of a channel assembly near the upper end of the partition 15. The invention is thus applied in providing suitable means for attaching picture molding 20 which may be readily secured in place through use of screws or nails 21. In a similar manner a channel assembly may be made a part 25 of the lower portion of partition 15, as shown, to facilitate attachment of the baseboard 18 in a manner similar to that for securing molding 20 in place.

The invention may be used for numerous purposes in building construction where it is necessary to attach one member to a second member which is of such nature that usual constructional expedients are of little or no avail. It is of special utility in connection with installation of partitions, particularly in cases where relocation of a partition is necessary. In usual constructions if relocation of a partition is desired it is necessary to destroy the partition in the removal thereof and to construct the new partition in a new location. This is avoided by the present invention in the following manner:

Referring to Fig. 1 coating 2 is removed from the floor to the approximate level indicated by dotted line 25. In a similar manner the coating is removed from the ceiling as indicated by dotted line 26. The flange-to-filler fasteners are then removed from the exposed flanges which are then bent into the plane of the channel web. Strip 11 is then free to move but for the fasteners in the opposite flange of the channel 5. The partition is then moved sidewardly as a unit to withdraw the remaining fasteners from strip 8, whereupon the partition is free for movement to its new location. At the new location new channels 5 will have been provided, one flange thereof being bent down to receive strips 8. When the partition is located with said strips positioned in the angle formed by the web and the remaining flange, the channel is again formed and flange fasteners provided as before. The respective coating at both the old and new locations can then be neatly repaired to complete the alteration.

If a straight member is to be secured to a base member which is biased or irregular, as is frequently the case, a further advantage of the invention is made apparent. In such case the desired number of channel members 5 are secured in place. A level-line is then drawn between end points and if any flanges extend above such line such flanges may be readily sheared to the desired height. Filler strips of proper dimension are then secured in the channels. This feature 75 has a material advantage over the previous

method of using wedges which will become loose as by drying or otherwise.

The foregoing is illustrative and not exhaustive of the advantages of the invention and of the manners in which the invention may be practically applied. Other advantages and practical applications will be apparent to one skilled in the art after referring to the foregoing disclosure.

I claim:

1. In a building construction a support member, a bendable strip attached thereto and having an edge thereof bent outwardly therefrom to form a flange, a filler strip lying within the angle thus formed, and fastener means passing through one of the flanges of said channel to secure the 15 filler strip therein.

2. In a building construction a support member, a bendable strip attached thereto and having an edge thereof bent outwardly therefrom to form a flange, a filler strip lying within the angle 20 thus formed, fastener means passing through the channel flanges to secure the filler strip therein, and a finish coat on said support member.

3. In a building construction a support member, a bendable strip attached thereto and having 25 the edges thereof bent outwardly to form a channel, a filler strip lying within said channel and secured thereto, and a finish coat on said support member, the surface of said coat being flush with the channel edges.

4. In a building construction a support member, a bendable strip attached thereto and having the edges thereof bent outwardly to form a channel, a filler strip lying within said channel, fasteners passing through the flanges of the 35 channel to secure the filler strip therein and a finish coat on said support member, the surface of said coat being flush with the channel edges.

5. In a building construction a support member, a channel member of bendable material attached to said support, a filler strip within the channel of said member, fastening means passing through the sides of said member to secure said 40 filler strip therein, and a structural element attached to said strip.

6. In a building construction a support member, a channel member of bendable material attached to said support, a filler strip within the channel of said member, fastening means passing through the sides of said member to secure 45 said filler strip therein, a finish coat on said support member, said channel member comprising a screed for applying said finish coat, and a structural element attached to said filler strip.

7. In a method of installing a partition the 55 steps of attaching bendable channels to the floor and ceiling in the locating plane of said partition, trimming the flanges of said channels to a level line and securing wood strips within said channels, said strips having their exposed faces 60 in the plane of the level line.

8. A method of installing and attaching a unitary partition to coated surfaces comprising the steps of removing the coating from the supports in the plane of the desired location, securing 65 bendable L-members to the floor and ceiling with the upstanding flanges in the plane of one face of the desired partition, positioning the partition unit against said upstanding flanges, flanging the horizontal edges of the bendable members against the other face of the partition, whereby anchoring channels are formed, and re-coating the supporting surfaces adjacent the anchoring channels.
